UNITED STATES PATENT OFFICE.

FRANK J. GILROY, OF BUFFALO, NEW YORK.

CAR-DOOR.

1,250,849.

Specification of Letters Patent. Patented Dec. 18, 1917.

Application filed March 17, 1915. Serial No. 14,980.

To all whom it may concern:

Be it known that I, FRANK J. GILROY, a citizen of the United States, residing at Buffalo, in the county of Erie and State of New York, have invented certain new and useful 5 Improvements in Car-Doors, of which the following is a specification, reference being had therein to the accompanying drawing.

This invention relates to car doors which, 10 when shut, are in close engagement at all peripheral points with devices on the car, and which normally rest upon rollers mounted upon the exterior of the car, below the path of the door, in position to support the door 15 whether in open or closed position. The objects are to provide a construction adaptable for use with thin metal doors or with new or old wooden doors; that obviates the necessity for internal boarding to prevent 20 the escape of loose granular material with which the car may be loaded; that fully excludes water; that will stand rough usage; that cannot, open or closed, move outward 25 from the car wall; and that is extremely simple and inexpensive.

In the accompanying drawings,

Figure 1 is a side elevation of a portion of a car provided with my novel devices.

Figs. 2, 3, 4, 5, 6 are, respectively, 30 sections on the lines 2-2, 3-3, 4-4, 5-5, 6-6, Fig. 1.

Fig. 7 is a view analogous to Fig. 1 showing a smaller portion of a car provided with a wooden door.

Figs. 8, 9, 10, 11 are sectional views showing construction when a wooden door is used and corresponding to Figs. 2, 3, 4, 5, 35 respectively.

Fig. 12 is a horizontal section through a 40 rear door-post and illustrates a modified construction.

Fig. 13 is a vertical section of the belt rail portion of the post of Fig. 12.

In these drawings, A represents the side 45 wall of a car provided with a door having a body B of thin sheet steel reinforced at its forward edge by a T-bar C, at its upper edge by a bar D, at its rear margin by an angle bar E, and at its lower edge by a 50 channel bar F made wide near the door angles and overlapped by the bars C, E, to which it is riveted or otherwise rigidly secured. Across the body of the door extend horizontal T-bars G which, like the marginal members just mentioned, are rigidly 55 secured to the body B and, at their ends, to

the bars C, E, which they overlap. To the angle bar E is fixed a second angle bar H, one flange H' of which forms a hook parallel to and slightly within the plane of 60 the body B.

To the exterior of the car, below the plane of the car floor I (Fig. 3) a door-engaging member J is secured. This member is provided, along its upper side, with a downwardly extending or hooked flange J' with which the bar F on the door engages, and below the hook the member extends outward beyond the plane of the door and is provided, below the edge of the door, with 70 broad vertical openings in which are cylindrical rollers J² mounted on shafts J³ and projecting slightly above the plane of the outwardly extending portion of the member J, which is rigidly secured in place by bolts 75 J⁴ passing through the member, the car sill I', a strengthening bar I² and a three web angle bar I³, and also further secured by rivets I⁴, preferably, as shown in Fig. 9.

The upper side of the door is overlapped by a downwardly inclined angle bar K secured by bolts K' passing through the upper portion of the car frame and like the member below extending rearwardly from the door opening so that when the door is 80 fully opened its upper and lower margins are still securely held close to the car wall. The upper edge of this bar lies wholly below the oblique face of a wood strip K² which prevents water from passing behind the bar. 90

The forward margin of the door when the latter is closed, as in Fig. 5, lies within the flange of a braced member L secured by bolts L' passing through the door post L², and at the opposite edge of the door the flange of the angle bar H engages the flange of an angle bar M forming a sort of jamb and secured by bolts M' passing through the door post M² and parallel to the wall of the car. 95

The parts upon the car wall being in place and the door being ready for use, the door is engaged with the upper and lower members on the car and moved forward toward the door opening. Stops N are then fixed to the car, and thereafter the door can be removed only by reversing the steps just indicated. When the door is closed it may be secured by ordinary devices with such safety devices as may be selected. 105

Nearly all parts of the door described are of commercial steel obtainable everywhere, and 110

hence its cost is very little more than the cost of a wood door, or is even less if "salvage" on old doors be considered. It is however desirable to obtain similar advantages without discarding wood doors already in use, and Figs. 7, 8, 9, 10, 11 show modifications which may be used with wood doors.

In these figures, O represents a wood door having its forward and upper margins covered by angle bars O' while its rear and lower edges are provided with channel bars O², O³. The front edge of the closed door engages under a bar P similar to the bar L of the primary form, and the channel bar 15 O² engages a bar Q analogous to the bar M of Fig. 4. As in the other form, the door normally rests on rollers R, which in this instance however are mounted in separate brackets R', secured by bolts R² passing 20 through the car sill and a three-web angle bar member R³ to the lower flange of which the brackets are also riveted. The channel bar O³ forms a smooth continuous surface, 25 at the lower edge of the door, to rest upon the rollers. In this case water is excluded 30 from the inner face of the bar K⁰ by a thin metal sheet S, which may be of copper, overlapping the upper flange of the bar and lying between the rabbeted edges of two wood facing members secured on the car frame.

Instead of the common door post illustrated, I may use the channel iron post V, shown in section in Figs. 12, 13. To this post the usual belt rail W is secured by a riveted bracket W', and above and below the belt rail wood members V' are secured to the post V to receive the external and internal sheathing X, X'. The channel iron post is made wide enough to project outside 35 the plane of the outer sheathing so that its outer flange V² may be engaged by the hook, such as H', at the rear edge of the door.

It may be noted that ice is unlikely to 40 interfere with the working of the door since

the latter rests upon ungrooved rollers and does not come into contact with parts surrounding the rollers.

What I claim is:

1. The combination with a freight car, of 50 parallel, oppositely turned external horizontal flanges fixed to the car above and below its door opening, respectively, a door provided near its upper and lower sides, respectively, with flanges engaging over and 55 under the flanges first mentioned, respectively, cylindrical door-supporting rollers fixed to the car below the door and projecting above the outer portions of their mountings and normally sustaining the weight of 60 the door and maintaining the flanges out of door-supporting and friction producing contact between their horizontal faces, and a flange fixed to the car above the door, overlapping the same externally and excluding 65 water while aiding in preventing the material rising of the door.

2. The combination with a freight car, of 70 parallel continuous flanges fixed to the car above and below its door opening, respectively, and extending from end to end of the path of a sliding door for said opening, a sliding door provided upon its inner face with continuous flanges non-detachably 75 engaged over and under the flanges first mentioned, respectively, and a series of plain cylindrical rollers mounted on the car below the door, projecting above adjacent parts extending farther outward from the plane of the door, and in position for carrying practically the entire weight of the door by maintaining the flanges out of door-supporting and frictional contact at their horizontal faces.

In testimony whereof I affix my signature 85 in presence of two witnesses.

FRANK J. GILROY.

Witnesses:

MICHAEL E. WELCH,
JEREMIAH V. McCARTHY.
